UNITED STATES PATENT OFFICE.

OSCAR A. ROSS, OF CHICAGO, ILLINOIS, ASSIGNOR OF ONE-HALF TO C. VALETTE KASSON, OF CHICAGO, ILLINOIS.

FENDER OR THE LIKE.

1,140,336.

Specification of Letters Patent. Patented May 18, 1915.

Application filed August 20, 1910. Serial No. 578,817.

To all whom it may concern:

Be it known that I, OSCAR A. ROSS, a citizen of the United States, residing at Chicago, in the county of Cook and State 5 of Illinois, have invented certain new and useful Improvements in Fenders or the like, of which the following is a description.

My invention belongs to that class of devices known as fenders, and relates particularly to an automobile fender, the same being an improvement over the fender shown in my Patent No. 995,371, issued June 13, 1911.

15 My invention has among its objects the production of a simple, efficient, durable and satisfactory fender of the kind described that may be applied to any style of vehicle without requiring special constructions or styles for different vehicles.

To this end my invention consists in the novel construction, arrangement and combination of parts herein shown and described and more particularly pointed out 20 in the claims.

Referring to the drawings in which like reference characters indicate like or corresponding parts; Figure 1 is a plan view of the fender as applied to an automobile. 25 Fig. 2 is a side elevation of the same, a portion of the fender bar being removed. Fig. 3 is a sectional view taken substantially on line 3—3 of Fig. 2. Fig. 4 is a sectional view taken substantially on line 4—4 of Fig. 3. Fig. 5 is a sectional view taken substantially on line 5—5 of Fig. 1, and Fig. 6 is a perspective view of one part of the clamp.

Referring to the drawings, 1 represents the fender or impact bar of the fender and 30 2—2 the vehicle frame. The bar 1 is resiliently supported by coiled springs 3 engaging a member 4 which is arranged to adjustably clamp or be secured to the impact bar. As most clearly shown in Fig. 5, the 35 clamps each comprise a part 4 arranged to embrace the bar and a clamping member 5 controlled by a set-screw 6 or its equivalent, the member 4 being provided with a threaded or grooved end 4¹ which is secured to the spring 3. The opposite end of each spring 3 is supported by a member 7, which is secured to the vehicle frame 2, the members 7, springs 3 and clamping members 4 com-

prising resilient supporting arms for the impact bar 1. The member 7 is also grooved at 55 8 similar to part 4, so that the spring 3 may be positioned thereon as on the extension 4¹. The members 7 are secured to the frame 2 by means of the bolts 11 and nuts 11¹, and to prevent the same from rotating 60 thereabout, thereby maintaining the impact bar 1 in operative position, I provide a part 12 for each member 7 arranged to engage the member 7, and extended backward and under the frame 2, as at 13. The members 65 7 and 12 are preferably provided with mating faces 9 and 10 which are serrated or toothed so that they will engage, making them adjustable but non-rotatable relative to each other. These faces prevent the parts 70 12 and 7 from rotating relatively, to each other, upon the vibration of the machine, and the extension 13 engaging under the frame 2 prevents the parts from rotating about the bolt 11 in a direction to lower the 75 impact bar 1, thereby securely and adjustably holding the impact bar in operative position.

Having thus described my invention, it is obvious that various immaterial modifications may be made in the same without departing from the spirit of my invention, hence I do not wish to be understood as limiting myself to the exact construction, arrangement or combination of parts herein shown and described.

What I claim as new, and desire to secure by Letters Patent is:

1. A vehicle fender comprising an impact bar, and means for adjustably and resiliently attaching the bar to the vehicle, said means comprising a pair of coiled springs, means for securing said springs to the bar, a part secured to the opposite end of each of said springs and provided with a serrated 90 face, a coöperating part provided with an engaging serrated face, and means for securing said parts to the vehicle frame with said faces in operative engagement.

2. A vehicle fender comprising an impact bar, and means for supporting said bar from the vehicle frame, comprising a fixed part on said frame provided with a serrated face, and adjustable coöperating part provided with a serrated face, means for securing said adjustable coöperating part to the 100 105

frame with its serrated face engaging the similarly formed face on said fixed part, and a spring having one end secured to the bar and the opposite end secured to said co-
5 operating part.

3. A vehicle fender comprising an impact bar and means for supporting said bar, said means comprising a part on the frame at each side of the vehicle provided with a
10 serrated face, means coöperating with the frame for limiting the movement of said parts, an adjustable coöperating part for each of said first mentioned parts, each of said adjustable coöperating parts provided
15 with a serrated face, means extending through the frame and said coöperating parts for securing each of said coöperating parts to the vehicle frame with its serrated face engaging the similarly formed face of
20 said first mentioned part, and resilient

means for securing said bar to said coöperating parts.

4. A vehicle fender, comprising an impact bar and resilient arms adjustably secured to said bar and supporting means for
25 said arms secured thereto and to the vehicle frame, said means comprising mating parts provided with coöperating serrated faces, one of said parts being arranged to coöperate with the vehicle frame and means
30 for securing said engaging parts to the frame.

In testimony whereof, I have hereunto signed my name in the presence of two subscribing witnesses.

OSCAR A. ROSS.
